UNITED STATES PATENT OFFICE.

WILLIAM J. LINDSAY, OF PHILADELPHIA, PENNSYLVANIA, ASSIGNOR TO CAMDEN IRON WORKS, OF CAMDEN, NEW JERSEY, A CORPORATION OF NEW JERSEY.

COAL-FEEDER FOR GAS-PRODUCERS.

1,256,340.

Specification of Letters Patent. Patented Feb. 12, 1918.

Application filed May 26, 1916. Serial No. 100,058.

To all whom it may concern:

Be it known that I, WILLIAM J. LINDSAY, a subject of the King of Great Britain and Ireland and the Isle of Man, residing in 5 Philadelphia, county of Philadelphia, State of Pennsylvania, have invented certain Improvements in Coal-Feeders for Gas-Producers, of which the following is a specification.

10 One object of my invention is to improve the construction of the mechanism for feeding coal to gas producers so that the lumps of coal will not bind upon the rotating feeding device.

15 A further object of the invention is to provide means for distributing the coal as it is discharged from the feeder into the body of the producer.

20 My invention also relates to further details of construction which will be fully described hereinafter, reference being had to the accompanying drawings, in which:

Figure 1 is a transverse sectional view of my improved coal feeding device for gas 25 producers, the section being on the line 1—1,

Fig. 2;

Fig. 2 is a sectional view on the line 2—2, Fig. 1; and

30 Fig. 3 is a side view illustrating the ratchet mechanism.

My invention can be applied to any type of gas producer and it is particularly adapted for a producer in which the top is stationary and the shell rotates.

35 Referring to the drawings, 1 is the top of the gas producer on which is mounted the casing 2. The casing has a transverse partition 3 having inclined surfaces 4 and mounted on a transverse shaft 5, directly above the 0 partition, is a deflector 6 which can be adjusted to any position desired so as to direct the coal to certain parts of the producer. For instance, in a producer in which the body rotates that portion of the surface on 5 which the coal is discharged farthest from the center of the producer will travel at a greater speed than that near the center, consequently, the deflector is so adjusted that a greater portion of the coal will be directed toward the periphery of the producer than toward the center. This deflector is adjusted by a hand lever 7 and is confined in its adjusted position by a hook bolt 8 on which is a nut. This hook bolt frictionally engages a flange 9 on the casing 2 but other

means of fastening the deflector may be used without departing from the essential features of the invention.

10 is the casing of the feeding device proper. This casing is made in two parts 11 and 12 in the present instance. The part 11 is flanged and is secured to a flange of the casing 2 and has hand holds 13 provided with pivoted cover plates 14 so that access can be had to the space between the feeder 15 and the distributor. 15 is a cylindrical feeder made hollow and having a slot 16 throughout its length, of any width desired. The forward edge 17 of this feeding cylinder is preferably round, as shown. 18 is a toothed drum which rotates in the same direction as the cylindrical feeder and is mounted on a shaft 19 so that as the coal discharges from the hopper 20 into the interior of the cylindrical feeder 15 and the feeder travels under the toothed roller, any projecting lumps of coal will be thrown out by the toothed roller so that the feeder 15 can turn freely into the discharging position. The toothed roller is located within 80 a recess formed in the hopper, as shown, and its shaft 19 is driven from a gear wheel 21 on the spindle 22 of the rotating feeder through an intermediate gear wheel 23 and a pinion 24 on said shaft 19, so that, in the present instance, the roller is rotated at a greater speed than the feeder. The spindle 22 of the feeder 15 is connected by a coupling 25 to a driving shaft 26 adapted to suitable bearings on the producer. On this 90 driving shaft is a ratchet wheel 27 and loosely mounted on the shaft 26 is an arm 28 connected by a rod 29 to power mechanism, and also on this arm is a pawl 30 engaging with the teeth of the ratchet wheel 27. 95

In order to regulate the feed, I provide an adjustable curved plate 31 which can be moved over the surface of the ratchet wheel 27 so as to cover more or less of the teeth and to prevent their engagement by the 100 pawl as the arm 28 will always have the same amount of movement. The plate 31 has a slotted projection 32 through which extends a bolt 33 provided with a wing nut which will retain the plate in any position 105 to which it is adjusted.

It will be seen by the above description that I provide a simple and effective device for feeding coal to gas producers which will not clog and which will distribute the coal 110

evenly over the surface of the material in the producer.

While I have shown a corrugated roller 18 in which the corrugations extend longitudinally of the roller, individual teeth may be substituted for the corrugations, and, in some instances, the roller may be smooth, the tendency of the roller being to push the projecting lumps of coal back into the hopper so that the feeder will properly discharge its load.

While I have shown the casing made in two parts 11 and 12, it may be made cylindrical and provided with detachable heads 15 for the placement or removal of the feeder.

I claim:

1. The combination in a feeder for gas producers, of a casing; a hollow cylindrical feeding device in the casing having a longitudinal slot therein; a hopper communicating with the feeder; a driven roller located at one side of the feeder and rotating in the same direction as the feeder and acting to

displace the lumps of coal projecting from the feeder; and means for rotating the feeding device.

2. The combination of a casing; a rotating cylindrical feeding device located within the casing and having a longitudinal slot therein; a hopper above the casing; a longitudinally arranged roller having a roughened periphery; means for rotating the roller so that as the feeder rotates the projecting lumps of coal will be thrown back into the hopper by the roller.

3. The combination of a casing; a hollow cylindrical feeding device mounted in the casing and having a longitudinal slot therein; a hopper on the casing; a roller at one side of the hopper directly above the feeding device; longitudinal corrugations in the surface of the roller; means for driving the roller at a greater speed than the feeding device; and means for intermittently turning the feeding device.

WILLIAM J. LINDSAY.
